UNITED STATES PATENT OFFICE.

JOSEPH NIEMIEC, OF NEWARK, NEW JERSEY.

AUTOMATIC RAILROAD-GATE.

1,261,275.

Specification of Letters Patent. Patented Apr. 2, 1918.

Application filed July 25, 1917. Serial No. 182,600.

To all whom it may concern:

Be it known that I, JOSEPH NIEMIEC, a subject of the Emperor of Austria, resident of Newark, county of Essex, and State of New Jersey, have invented certain new and useful Improvements in Automatic Railroad-Gates, of which the following is a specification.

This invention relates to improvements in automatic gates, and particularly to those adapted to be operated by an approaching locomotive at railway track crossings.

The principal object of the invention is to provide means capable of being installed at the sides of a railway track, as at a street crossing, which will automatically, upon the approach of a locomotive and without action of the engineer, cause the gates to close in advance of the passage of the train, and to open after the train has passed.

This and other like objects are attained by the novel construction and combination of parts hereafter described and shown in the accompanying drawings, forming a material part of this disclosure, and in which:

Figure 1 is a diagrammatic side elevational view showing a track having a locomotive thereon and an open gate.

Fig. 2 is an enlarged fragmental sectional view taken on line 2—2 of Fig. 7.

Fig. 3 is a top plan view of the mechanism, parts being removed in order to show the construction.

Fig. 4 is a similar top plan view, the parts being shown in another position from that in Fig. 3.

Fig. 5 is a transverse sectional view taken on line 5—5 of Fig. 3.

Fig. 6 is a view similar to Fig. 2, but showing a single operative structure, and in a different position.

Fig. 7 is a side elevational view of the complete device, showing the gate in an open position, the casing being shown in section.

Fig. 8 is a similar side elevational view of the same, the gate being shown in a closed position.

Fig. 9 is a fragmental side elevational view of contacting elements carried by the locomotive, and

Fig. 10 is a side elevational view largely diagrammatic indicating the application of the invention.

In Fig. 1 a railway track 15 is shown,

upon which is a locomotive 16, having a part contactable with an overhead wire 17, extending to some distance at each side of the gateway 18, interposed in the fence 19, by means of which the railroad bed is protected against the intrusion of vehicles, animals and travelers who might otherwise cross the track at such times as to be in danger from an approaching locomotive.

The invention has to do specifically with the gate and means for operating the same carried by the locomotive, the gate including two pairs of hollow uprights or standards 20 and 22, arranged upon opposite sides of the roadway crossing and connected by a similar hollow bridge element 21 at the top, a similar structure being upon the opposite side of the railway track, the two being connected by an overhead shaft 23 and by means of which the gate elements are operated simultaneously.

Carried by the locomotive 16, preferably at the top of the cab, is a bracket 25 having pivotally secured at its upper end a lever 26, held normally upward by the coiled pressure spring 27, and provided with a pull cord 28 by means of which it may be depressed as desired.

On the upper side of the lever 26 is secured a vertical arm 29, carrying a pulley 30, adapted to make contact with the overhead wire 17, which, as will be seen, extends only a relatively short distance from either side of the gateway and is supported by the post 31, current being supplied to the pulley 30 by the source of electricity 32, in circuit with one of the running rails of the track 15.

Centrally of the bridgepiece or connecting element 21, and on top thereof, is a hollow box-like structure 33, containing an electric motor 35, and carried by the shaft of motor 35 is a spur gear 36 transmitting, through the idle pinion 37, rotary motion to the spur gear 38, rotatably mounted on the ends of the shaft 23, housed in suitable bearings formed in the bridge 21, and having affixed upon its sides dogs 39, engageable with a ratchet 40, which is rigidly engaged with a collar also rotatable upon the shaft 23 and having its inner extending end 42 formed with ratchet teeth engageable with a similar ratchet element 44, formed with a drum 45, having extending annular flanges 46, 47, and 48 respectively, the first being of increased thickness and having a

beveled surface 49, while the second flange 47 acts as a partition dividing the drum into two substantially uniform spaces 50 and 52, upon which are wound cables 51 and 53, having their outer ends engaged with spindles 55 and 56, laterally slidable upon guides 57 and 58 longitudinally of the bridge 21.

Formed with the spindles 55 and 56 are 10 similar annular disks 59 and 60, the extreme edges of which are adapted to engage with the beveled surface 49 when brought into contact by reason of the drum winding up the cable to such an extent as to cause the cable drum 45 to slide upon the shaft, there- 15 by withdrawing its connection so both the spindles 55 and 56 will move outwardly toward the standards 20 and 22 respectively, and in order that a complete separation of the gate parts may be made, there is also 20 mounted upon the shaft 23 fly wheels 62 so that its momentum may serve to operate the drum momentarily after the teeth have been disconnected.

Also attached to the spindles 55 and 56 25 are the ends of the cables 65 and 66, the same running over fixed pulleys 68 eventually terminating in weighted elements 69, by which an operative tension is maintained in the cables at all times.

30 Rigidly attached to the spindles 55 and 56 are depending arms 71 and 72, having in-turned ends 73 and 74 to which are attached rigid rods 75 and 76, the lower end of the rods terminating slightly above the level 35 of the street roadway. Engaged at spaced intervals to these arms are cables 78, the same extending through openings 80 formed in the inner wall of the standards 20 and 22, and which pass over pulleys 81, arranged at 40 substantially equal distances apart, the other ends of the cables being attached to the weight 69.

In order to hold the pendent bars 75 and 45 76 from retracting under the pull of the weights 69, the ends 73 and 74 of the arms are provided with slots in their upper surfaces 83 and 84, engageable with an extension 85, of a lever 86, pivoted on the pin 87, the other end of the lever being normally 50 raised by reason of the pull spring 88, one end being engaged with the lever and the other with the arm 89 of another lever 90, pivoted on the pin 91, and having a forked upper end 92, engageable with the center 55 flanges 47 of the drum in such manner to be rocked thereby.

The peculiar shape of the lever 86 is suited 60 to engage with the projection 94 from the end of the lever 90, and by means of which it may be raised, depressing the end 85, thereby locking the pendent bars in a closed position when the drum 45 is disengaged from the driving teeth, as can best be seen in Fig. 6, the released position of the 65 bars being shown in Fig. 7.

The lateral movement of the fly wheel 62 on the shaft 23 is conveyed to the drums 45 by means of the collars 95 in which is a screw 96, operating in a spiral groove 97 formed directly in the shaft 23, and by 70 means of which the teeth may be engaged together when the shaft is actuated as above described. In operation an approaching locomotive 16, carrying the contact pulley 30, forms an electric circuit between the overhead wires 17, and running rails 15, energizing the motors 35, and by them, actuating the gear trains, bringing the gate elements 75 and 76, toward each other, meeting at the middle of the passage between the standards 20 and 22.

These gate elements 75 and 76 carry arms containing slots which automatically engage with the element 85 of the spring actuated lever 86, locking the gate elements 85 together and they so remain locked until the locomotive has passed the track section having the wires 17, at which time the circuit becomes broken, releases the drums, which moving laterally on their mounting, in turn 90 releases the lever and permits the gate elements to separate and return to their initial position due to their connections with the weights 69.

From the foregoing, it will be seen that an 95 efficient gate operating device has been disclosed and that it may be opened and closed upon both sides of the railroad track whenever a locomotive is approaching the crossing.

100

Having thus described my invention, what I claim as new, and desire to secure by Letters Patent is:—

1. In an automatic gate, the combination with a pair of hollow standards, a bridge 105 connecting therebetween and carriages movable in said bridge, pendant rods extending from said carriages, a plurality of flexible elements engaged with said pendant rods, means for operating said carriages simultaneously, and means for retracting said flexible elements within said hollow standards.

110

2. In an automatic gate, the combination with a pair of hollow standards disposed upon either side of a roadway, a hollow bridge connecting therebetween, oppositely movable carriages operable in said bridge, arms depending from said carriages, flexible cables spacedly engaged with said arms, 115 said cables extending through openings in the adjacent side of said standards, pulleys in said standards over which said cables run, and a counterweight engaged with all of said cables whereby the same may be retracted as 120 said carriages move outwardly.

125

3. In an automatic gate, the combination with an electric motor, a source of power therefor, means for connecting said source of power with said motor, a drum driven by 130

said motor, means for engaging or disengaging the driving means with said drum, said means including a pair of oppositely movable carriages, operable connections between 5 said rods and said carriages, and a pair of oppositely disposed gates movable by said carriages.

4. In an automatic gate, the combination with a pair of standards, a bridge connecting 10 therebetween, a motor mounted on said bridge, and a source of electrical power, of means for automatically connecting said source of electrical power in circuit with said motor, a double drum driven by said 15 motor, a pair of oppositely disposed carriages slidably engaged in said bridge, connections between said drum and carriages whereby the latter may be advanced, means for retracting said carriages, a pair of rigid 20 pendant arms attached to said carriages, means for holding said arms in engagement when in an advanced position, a plurality of flexible spaced cables engaged with said

pendant bars, said cables being normally contained in said hollow standards, and 25 means for retracting said cables therein when said carriages are moving outwardly.

5. In an automatic gate, the combination with a pair of hollow standards, a bridge connecting therebetween, and a motor 30 mounted on said bridge, of means for conveying power to said motor, a train of gears driven thereby, a shaft upon which the last gear of said gear train is mounted, a double drum on said shaft, connections between 35 said drum and the last gear in said train whereby it may be driven in one direction, a pair of oppositely disposed carriages mounted in said bridge, means carried by said carriage for disconnecting said drum from said 40 gears, and means carried by said carriages for closing the passage between said standards.

In testimony whereof I have affixed my signature.

JOSEPH NIEMIEC.
